Primary Examiner — Patricia Palasik(74) *Attorney, Agent, or Firm* — Altera Law Group, LLC(57) **CLAIM**

The ornamental design for a workpiece support, as shown and described.

DESCRIPTION

FIG. 1 is a perspective view;

FIG. 2 is a top plan view thereof (the bottom plan view is a mirror image of the top plan view); and,

FIG. 3 is a side elevational view thereof (the view from the side is the same on all sides thereof).

The broken lines in the drawings depict unclaimed environmental subject matter.
